Patented Feb. 24, 1920.

INVENTOR

WALLACE O. POWERS
By Joseph J. O'Brien
ATTORNEY

UNITED STATES PATENT OFFICE.

WALLACE O. POWERS, OF SPRINGFIELD, MASSACHUSETTS.

TOOL.

1,331,824.

Specification of Letters Patent. Patented Feb. 24, 1920.

Application filed January 31, 1919. Serial No. 274,370.

To all whom it may concern:

Be it known that I, WALLACE O. POWERS, a citizen of the United States of America, and resident of Springfield, in the county 5 of Hampden and State of Massachusetts, have invented certain new and useful Improvements in Tools, of which the following is a full, clear, and exact description.

This invention relates to improvements in 10 tools, and, more particularly, to tools of the class having means for applying pressure to hold or force the tool to the work while it is being rotated.

While the invention is capable of general 15 application, it is particularly adapted for use in removing screws, bolts, or the like, which have so long remained in place that they are exceedingly difficult to remove and many times impossible to move by ordinary 20 means. The tool of this invention, conversely, affords a particularly advantageous means of firmly applying and tightly seating the nuts, screws, bolts and so forth. I am aware that tools, having pressure applying 25 means, have been provided heretofore and this invention is concerned primarily with improvements in tools of this general type to the end of improving their efficiency and broadening their field of service.

The invention has for its object to provide 30 a tool holding element which is revolvably connected to a lever to permit its rotation relatively thereto and to likewise permit a substantially universal movement 35 of the lever with relation to the tool. The lever is provided with flexible means for connection with the work upon which the tool is to operate or to some member stationary relative thereto, whereby a fulcrum 40 is provided for the lever so that the latter may force the tool to the work. The tool holding element is preferably relatively long so that it may be inserted into deep holes to reach screws and the like therein, and 45 such element has a relatively long polygonal wrench receiving portion which permits the wrench to be slid up and down on the element as necessitated by varying characters of work being operated upon.

50 Other objects and advantages will appear in the following description and in the illus-

trative embodiment of the invention, in the accompanying drawings, in which:

Figure 1 is an elevational view, partly in section, showing a tool embodying the invention; and

Fig. 2 is a cross sectional view of the polygonal tool holding element.

Referring to the accompanying drawings illustrating the practical embodiment of my 60 invention 5 designates a metal or steel lever of great strength and rigidity, which is formed with a ball socket 6 on one side thereof.

A ball 7 is normally disposed in the socket 6 and is formed on a pin 8 which is driven into the longitudinal opening 9 of a tool holding element 10, or otherwise positively connected to the latter. The pin 8 extends through a retaining member 11, secured to 70 the side of the lever 5 by means of screws 12 and 13, which are provided with heads to hold the retaining member 11 against the side of the lever 5. The retaining member 11 is formed with a recess 14, forming a 75 part of the socket for the ball 7, which is loosely retained between said bar 11 and the lever 5 to move easily in the socket or recess 6 of the lever 5. The member 11 is also formed with a beveled opening 11', whereby 80 the pin 8 may swing over a long arc.

The element 10 is formed with a rounded end 10' which is spaced slightly from the opposing face of the bar 11, so that the element 10 may swing with the pin 8. The pin 85 8 is locked or driven into the element 10 only after it has been extended through the retaining member 11, so that when the screws 12 and 13 are removed the member 11 will be held by the ball on the element 10. 90

The element 10 has secured thereto a square tubular coupling member 15, which projects from the end of the element 10 to provide a socket 16 to receive a tool, such as the screw engaging blade T. In order to 95 lock the tube to the element 10 said element is provided with transverse grooves 10^a and the tube 15 is formed with indentations 18, which are forced into the grooves 10^a, whereby the tube 15 is locked to the element 10 100 against longitudinal movement thereon.

The lever 5 is provided with a pin 19 lo-

cated near the outer end thereof, and to this pin one end of a suitable flexible connecting member, such as the chain 20, is connected, and the member is then wound around the work, as W, and connected either to itself or to the pin 19 to provide a non-extensible connection between the lever and the work.

In using my improved device the tool T, if a screw driver, as illustrated, is placed in the slot of the screw head S and pressure applied on the lever so that the tool T is held hard against the head of the screw. The element 10, coupling sleeve or tube 15 and the tool T are preferably square in cross section, so that by applying a suitable wrench to either of these members the tool may be rotated, thus rotating the screw S, which is held under positive control at all times. It is impossible for the tool or screw driver blade to jump out of the slot of the screw S, as the blade is held under pressure applied on the lever 5. By relieving this pressure the tool may be readily removed from engagement with the screw.

The recess 14 of the retaining member 11 is located centrally therein, and the screw 13 is adapted to serve as a pivot when the screw 14 is removed and the member 11 swung toward the inner end of the handle lever. The lever 5 is formed with a second socket 5^a adapted to be engaged by the ball 7, and is also provided with a screw threaded opening 21 to receive the screw 14, whereby the leverage may be varied, or the relation of the element 10 and its tool with

respect to the chain or flexible connecting member varied, as may be found necessary in operating under confined conditions.

I claim and desire to secure by Letters Patent:

1. A tool of the character described, comprising a lever, an element carrying a tool at one end, means revolvably connecting the element at its other end to said lever; such means permitting the lever to be moved in all directions relatively to said element, and flexible means to connect the lever to the work to be operated upon or some member relatively stationary thereto, whereby said flexible means affords a fulcrum for the lever and pressure may be exerted by the latter upon said element.

2. A tool of the character described, comprising, a lever, an element connected to the lever at one end by a ball and socket joint and provided with a socket at its other end to receive a tool, said element affording a relatively long portion of polygonal cross section to receive a wrench and permit the latter to move up and down as necessitated by the character of the work being operated upon, and flexible means for connecting the lever to the work upon which the tool is to operate or to other means stationary relatively thereto.

Signed by me at Springfield, Mass., in presence of a subscribing witness.

WALLACE O. POWERS.

Witness:

F. W. BARTLETT.
